UNITED STATES PATENT OFFICE.

DE WITT C. MOSHER, OF COLORADO CITY, COLORADO, ASSIGNOR TO
CHARLES M. MAC NEILL, OF COLORADO SPRINGS, COLORADO.

CHLORINATION-BARREL.

SPECIFICATION forming part of Letters Patent No. 746,867, dated December 15, 1903.

Application filed November 9, 1900. Serial No. 35,983. (No model.)

To all whom it may concern:

Be it known that I, DE WITT CLINTON MOSHER, a citizen of the United States, residing at Colorado City, in the county of El Paso 5 and State of Colorado, have invented certain new and useful Improvements in Chlorination-Barrels, of which the following is a specification.

My invention relates to chlorinating-barrels; and my invention consists in providing a chlorinating-barrel with a strainer in the form of one or more longitudinal channeled and perforated ribs, to which lateral channeled and perforated ribs [may be added] so as to increase the available area of the barrel and reduce the cost of construction without impairing the durability, as fully set forth hereinafter and as illustrated in the accompanying drawings, in which—

20 Figure 1 is a section of a part of a chlorinating-barrel sufficient to illustrate my improvement; Fig. 2, a longitudinal sectional plan; Fig. 3, a transverse section showing a plurality of straining-ribs; Fig. 4, a transverse 25 section illustrating a different form of straining-rib with means for clamping it within the barrel; Fig. 5, a longitudinal vertical section at the center of Fig. 3; Fig. 6, a longitudinal vertical section at the center of Fig. 4.

30 The barrel A is of any usual construction, of wood or metal, and is adapted to be mounted and rotated as usual with chlorinating-barrels and is provided with a resistant lining of metal, as of lead, and with the outlet-opening 35 α at one side, which is employed as usual to discharge the contents or admit wash-water and which is controlled by a suitable valve.

Instead of the usual flat perforated straining-platforms, which occupy an objectionable 40 amount of space and require the use of strong supports, I provide a strainer in the form of one or more longitudinal pipes, shown as channeled ribs B, communicating with the outlet-opening α and with the interior of the barrel through perforations 11. The channeled rib may be of cast metal, with a plurality of parallel pipes, or channels, as illustrated in Fig. 4, or preferably consists of a plate of uniform thickness bent or formed 45 into an arch, as shown in the other figures, the arch form securing the desired interior

channel and affording sufficient strength in all directions to resist the pressure and impact of the ore.

The rib is secured fixedly within the barrel—as, for instance, by means of clamps 2 and bolts 3, as shown in Fig. 4, or by burning, soldering, or welding to the lining 5.

Preferably there is a plurality of lateral ribs C, each channeled and perforated and 60 communicating with the channel of the longitudinal rib, separated sufficiently for the entrance of the particles of ore between them and serving not only to secure a more extended screen area, but also serving to brace 65 and strengthen the longitudinal rib. When there is a plurality of longitudinal ribs, the lateral ribs C may extend between the longitudinal ribs, as indicated in Fig. 3.

By the use of one or more channeled and perforated ribs, as above set forth, I am enabled to secure a greater amount of available space within the barrel, and can thus do the same work with smaller and lighter barrels than heretofore. By making the ribs of arched 70 plates I can secure the strength to resist the effects of the pressure and percussion of the ore with ribs of comparatively light weight, and the weight may be still further reduced 75 without impairing the resisting capacity by 80 the use of abutments to the longitudinal rib in the form of the lateral perforated and channeled rib.

Without limiting myself to the precise construction and arrangement of parts shown, I 85 claim as my invention—

1. A chlorinating-barrel provided with a resistant lining and with an arched channeled rib extending longitudinally, secured to said lining and having perforations between the 90 interior of the rib and barrel, and a discharge-opening communicating with the interior of the rib, substantially as set forth.

2. A chlorinating-barrel provided with a resistant lining and with a channeled rib extending longitudinally, secured to said lining and having perforations between the interior of the rib and barrel, a discharge-opening 95 communicating with the interior of the rib, and lateral perforated channeled ribs, substantially as set forth.

3. The combination with a chlorinating-

barrel having a metallic lining, of an arched channeled and perforated longitudinal rib secured to said lining, lateral perforated channeled ribs communicating with the channel of the longitudinal rib and also secured in said lining, and an outlet-opening communicating with the interior of the longitudinal rib, substantially as set forth.

4. The combination with a chlorinating-barrel having a metallic lining, of an arched channeled and perforated longitudinal rib secured fixedly in place, lateral perforated channeled ribs communicating with the channel of the longitudinal rib, the said ribs secured fixedly within the barrel, and an outlet-opening communicating with the interior of the longitudinal rib, substantially as set forth.

5. The combination with a chlorinating-barrel and its metallic lining, of a plurality of channeled and perforated ribs connected immovably with the lining, the channels communicating with the outlet-opening of the barrel, substantially as set forth.

6. The combination with a chlorinating-barrel and its metallic lining, of a plurality of channeled and perforated ribs formed of a sheet of metal bent into parallel arches, the channels communicating with the outlet-opening of the barrel, substantially as set forth.

30 7. The combination with a chlorinating-barrel and its metallic lining, of a plurality of channeled and perforated longitudinal ribs formed of a sheet of metal bent into parallel arches, lateral perforated channeled ribs between the longitudinal ribs, and an outlet-opening communicating with the interior of the longitudinal rib, substantially as set forth.

35 8. A chlorination-barrel having a lining

and provided with a series of channels communicating with the barrel through perforations throughout the length of each channel, said channels formed in part by the barrel-lining, substantially as described.

9. The combination with a chlorinating-barrel, of a series of perforated pipes arranged at one side of the barrel and communicating with a port or opening extending through the barrel and provided with a cock.

10. In a chlorination-barrel, a parallel series of pipes C having numerous small orifices throughout their longitudinal walls, a transverse pipe B communicating with the pipes C and a port communicating with said pipe B and provided with a valve, substantially as set forth.

11. The combination with a chlorinating-barrel having a lead lining, of a perforated arch burned to the lining, substantially as described.

12. The combination with a chlorinating-barrel having a lining, of a filter in which a perforated arched member is burned to the lining and communicates with the outlet of the barrel, substantially as described.

13. In a filter-barrel a series of crowned plates, perforated with numerous small slots or holes, placed transversely across a lower arc of said barrel, and fastened thereto by having their adjacent surfaces "burned," soldered, or brazed.

In testimony whereof I have signed my name to this specification in the presence of two subscribing witnesses.

DE WITT C. MOSHER.
